UNITED STATES PATENT OFFICE.

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

INCLINED COKING-RETORT OVEN.

Application filed October 13, 1922. Serial No. 594,375.

This invention comprehends improvements in the art of inclined coking retort ovens, and has for objects the provision of an inclined retort that is highly efficient in operation and which will produce high grade coke and effect a substantially complete by-product recovery, although the entire distilling operation is conducted rapidly and with great conservation and equality in distribution of the heat.

Important characteristics of the invention are: the employment in an inclined coking retort oven construction of the cross-over flow principle exemplified in my prior Letters Patent of the United States No. 1,374,546, dated April 12, 1921, to permit a considerable reduction not only in the length, but also in the cross-sectional dimensions of the inclined or bus flues located at the top of the vertical flame flues and connecting a plurality of the latter with each other, and to permit flow in the same direction through all the flame flues of each heating wall, with the result that all the flame flues of each heating wall are either simultaneously burning or simultaneously operating as down flow flues for carrying away the waste gases to out flow operating regenerators; the attainment of equality in distribution of the heating effect in the heating walls, by a system that secures regulation of the flow through individual regenerators with their individually connected groups of flame flues at different elevations in the retort structure; and, as a further feature of the invention, the employment of the combination oven principle in an inclined retort construction, whereby the heat for coking the charges of coal in the retorts or coking chambers may be developed from the combustion of the distillate gas from such retorts, or alternatively, from a special generator gas, such as ordinary producer gas.

In addition to the general objects recited above, the invention has for further objects such other improvements or advantages in construction and operation as may be found to obtain in the structures and devices hereinafter described or claimed.

In the accompanying drawings, forming a part of this specification and showing, for purposes of exemplification, a preferred form and manner in which the invention may be embodied and practiced, but without

limiting the claimed invention specifically to such specific instance or instances:

Figure 1 is a vertical sectional elevation of an inclined retort construction embodying features above specified and constructed in accordance with the improvements of the present invention, the view being taken crosswise through a heating wall and the regenerators in a vertical plane indicated by the line C—C of Figure 2;

Figure 2 is a composite vertical sectional elevation taken longitudinally of a battery of inclined retorts, in planes indicated by the lines A—A and B—B of Figure 1;

Figure 3 is another crosswise section of the retort battery, the view being taken through a retort in a plane indicated by the line D—D of Figure 2;

Figure 4 is a composite sectional view taken on the inclined planes indicated by the lines E—E, F—F and G—G of Figure 1.

In its present embodiment, the invention is incorporated in a combination inclined coking retort oven designed for the employment of either the coke oven gas, or of an extraneously derived gas, such as producer gas, for the heating fuel. For convenience, the present description will be confined to this embodiment of the invention; features of construction and operation are, however, capable of other valuable applications such as in an inclined retort designed solely for the employment of the coke oven gas as fuel, or solely for the employment of the relatively lean extraneously derived gas as fuel; consequently, the invention is not confined in its scope to the specific use and specific embodiment herein described as an illustrative example.

Referring to the drawings: There are illustrated views of an inclined retort oven of the by-product type, as hereinabove mentioned, which retort embodies in its construction a plurality of intermediate vertically elongated inclined retorts or coking chambers 12, said coking chambers inclining downwardly from the charging and distillate outflow end to the discharge end, as shown in Figure 3. The heating walls 11 inclined at their top and bottom form the side walls of the respective coking chambers 12, as shown more particularly in Figure 2. In the present instance, the heating walls are directly supported by the pillar walls 13

which extend crosswise of the battery and are located, as shown in Figure 2, beneath the respective heating walls 11. These pillar walls, together with the other walls 22, hereinafter described, collectively form the main support for the entire superstructure of the battery and are themselves supported upon a mat 14, on which the entire battery rests.

The coal to be coked is charged into the 10 retorts 12 through charging holes 16 located in the top of the battery and at the upper ends of the several retort chambers, and the finished coke is discharged through the door openings 17 that are located at the bottom 15 of the several inclined retorts 12. The inclination of the retorts 12 is substantially that of the angle of repose of the coal charged into said retorts and, when the doors are removed from the discharge openings 17, the finished coke will slide by gravity out of the retorts 12. During the coking or distilling operation, the holes 16 of the respective retorts are employed as distillate outlets, and, in order to conserve the distillate and gases, said holes 16 are, throughout the distilling or coking operation, communicably connected with any suitable type of gas off-take main. Adjacent to each charging or distillate outlet 16, there is 30 provided in the top of each retort 12 a smoke hole 18, which is closed by any suitable cover during the distilling operation, but preferably opened during the charging operation, to permit the escape of the smoke 35 which rises as the coal is charged into the hot retort.

Heat for coking the charges of coal in the several retorts 12 is derived from the heating walls 11 above mentioned. Referring now more particularly to Figure 1, each heating wall 11 is constituted of a plurality of vertical flame or combustion flues 19. The flame flues of each heating wall, in accordance with the invention, all operate 40 concurrently for flow in the same direction, that is to say, there is no countercurrent flow between flame flues in any single heating wall. However, when the flame flues on one side of a coking chamber are burning, 45 that is to say, operating for upflow, the flame flues on the opposite side of the same coking chamber are operating for downflow to permit exhaust of the waste gases. Consequently, flame is maintained in all 50 the flues on one side of the charge of coking coal in each coking chamber, the heat being applied to the full length of one side of such charge during an entire heating interval and, after reversal of the flow, being applied to the full length of the opposite side 55 of the charge, until a further reversal is effected.

The regenerators 20 are incorporated in the refractory structure inclined at the top 60 and bottom that is located beneath the re-

torts 12 and the heating walls 11. Each regenerator 20 is a chamber containing open brick work, commonly called checker work, and indicated at 21, with a distributing sole channel 23 underneath such checker work, 70 the channels forming the soles of such chambers and opening up into the checker work. The regenerators are disposed, crosswise of the battery, at different levels or tiers, and, in the present instance, each crosswise group 75 of regenerators is composed of four regenerators respectively separated from each other by the interior vertical partitions 24. As shown in Figures 3 and 4, the sole channels from individual regenerators in the 80 different levels or tiers of each crosswise group extend up to a flow box 25 common to the flues of a given group, each flow box being provided with valve mechanism for controlling the direction of flow through the 85 whole crosswise group of regenerators. The flow box 25 is provided with an air lid 26 and with a mushroom valve 27 which respectively permit the admission of air into the regenerators or the outflow of waste 90 gases through the duct 28 leading to the stack flue 29. The stack flue extends longitudinally of the battery and has similar flow box connection with each crosswise group of regenerators. In the form of the invention shown in Figure 1, the sole channels from the individual regenerators of each crosswise group respectively extend from different levels to the common flow box, whereas, in the form of the invention shown 95 in Figure 3, the sole channels from the two lower regenerators of a crosswise group extend from the same lower level, and the sole channels from the two upper regenerators extend from the same upper level. 100

The several gas tight supporting walls 22 respectively extend directly beneath the coking chambers in parallelism between each two adjacent pillar walls 13. These supporting walls 22 provide two crosswise groups of regenerators G and H located respectively on the opposite sides of said walls 22 and between adjacent pillar walls 13. The several walls 22 also have the function of supporting the weight of the battery superstructure. This supporting wall construction provides two series of crosswise extending parallel gas tight load carrying walls located below the coking chambers and intermediate heating walls, the supporting walls of one series 13 being directly beneath the heating walls and the supporting walls of the other series 22 being directly beneath the coking chambers. The walls 110 22 which are beneath the coking chambers are constructed and function not as mere partitions commonly employed, but as true load carrying gas tight walls, permitting relatively different pressures to be maintained in the checker work chambers on the 115 120 125 130

opposite sides of said walls, or the flow of different media in the checker work chambers separated by these walls, without leakages from one checker work chamber into another and without danger of mixing gases in the checker work chambers which must be kept separate in this region of the battery.

The regenerators G and H are heated, in alternation, by the hot combustion products that are exhausted from the flame or combustion flues hereinbefore mentioned and then impart such heat to the medium that they feed into these flame flues. In the present instance, the flow through the regenerators G, H between each two adjacent pillar walls 13 is maintained concurrently in opposite directions, for example, when the flow is passing up through a regenerator 20 G, downflow is being maintained concurrently through the regenerator H. Each regenerator is provided with a series of ducts 30 all of which lead respectively to individual flame flues 19 of the same heating wall, whereas the ducts 30 of the other regenerator between the same pillar walls 13, lead respectively to individual flame flues 19 of the next adjacent heating wall, as clearly shown in Figure 2. With this construction, each flame flue 19 communicates by a pair of ducts 30 with adjacent separate regenerators of the pair of groups H, G, and the flow through the regenerators H, G which are respectively located on opposite sides of the pillar wall 13 is maintained concurrently in the same direction, that is to say, all the regenerators of both groups are either operating for inflow or for outflow.

In the present embodiment of the invention, the entire series of flame flues 19 of each heating wall 11 is either burning or operating for downflow to convey waste products to the regenerators beneath and consequently the crosswise groups of communicably connected regenerators operate concurrently for flow in the same direction and in the same manner. The reversal in flow through the flame flues 19 on opposite sides of a coking chamber or retort, and their communicably connected regenerators may thus be said to take place longitudinally of the oven battery, instead of transversely thereof, as has heretofore been a common practice in this art. The reversal of the battery is effected at the end of each operating or flow period, the duration of which is determined by practice, and by means of any preferred type of reversing mechanism. The function of such reversal is as follows: The regenerators that prior to the reversal operated as inflow regenerators become outflow regenerators, and the outflow operating regenerators become inflow operating regenerators; the upburning series of flues

switches function with the downburning series of flues of the next adjacent heating wall, and the supply of gas is turned off from the previously upburning flues and turned on into the mains of the previously downburning flues.

Each flame flue 19 of each heating wall has at its top a port or opening 31 for draft and the passage of combustion products or waste gas from the flame within the flue. These ports 31 open up into inclined or bus flues 32 provided in the heating walls and connecting all of the vertical flues that communicate with such inclined flues 32 by means of the ports 31. According to the invention, there is in each heating wall a plurality of, in the present instance four of such inclined bus flues 32 positioned end to end with respect to each other and constituted of the inside pair of bus flues K and the outside pair of bus flues L. By reason of the fact that each heating wall is provided with a plurality of such bus flues 32, these flues 32 are not required to be of so great capacity as that necessary in well known horizontal coke oven practice and consequently the cross sectional area of each bus flue 32 may be materially reduced proportionately with the length of such flue, with the result that the thickness and strength of the heating walls are substantially increased in the region of the inclined bus flues. The inside and outside bus flues are, as shown in Figure 1, communicably connected with inside and outside groups K' and L' of combustion flues of their companion heating wall. Because of the fact that each bus flue 32 communicates with a substantially reduced number of vertical flues, in the present instance one quarter of the flues of a heating wall, uniformity in distribution of the flow is greatly promoted. Moreover, each regenerator and its companion group of flame flues with their communicably connected inclined bus flues constitutes an operating or flow unit that may be regulated independently of the other flow units of the same heating wall. This arrangement not only permits regulation of the inside groups of combustion flues K' independently of the outside groups L', but also permits regulation of the heating effect throughout each heating wall to provide equality in distribution and to avoid the tendency, heretofore present in inclined retort constructions, for the heat to concentrate or overheating to occur in that region at the top of the incline. This arrangement prevents over-coking in the upper region of the battery and any tendency for the distillates becoming exposed and impaired by regions of excessive heat concentration.

As shown, the inside bus flues K and the outside bus flues L of each heating wall

are communicably connected by duct means or passageways 33 respectively with the corresponding bus flues of one of the next adjacent heating walls, that is, those on the same level. These passageways 33 extend over the top of a coking chamber between a pair of heating walls so interconnected and this construction provides individual flow connections between the groups of flues of each heating wall and the corresponding groups of one of the adjacent heating walls. Thus, the entire flow from the heating wall, within the flues of which combustion is being maintained passes through and downwardly through all of the flues of the next adjacent heating wall and each reversal operation is accompanied by a reversal in direction of the flow through all of the flues of each heating wall.

20 The draft through the ports 31 may be regulated by means of the usual movable dampers or sliding bricks 34, positioned in the ordinary way in the bottoms of the bus flues 32 and adapted to be reached by access flues 35 which extend from the top of the bus flues 32 in each heating wall to the top of the battery, there being an access flue 35 positioned over each flame flue of each heating wall. The crossover ducts 33 may 25 be reached by similar access flues 36 individual to the respective crossover ducts.

Extending crosswise of the battery in each pillar wall 13 and located beneath the heating wall 11 thereabove is a gas supply channel 37. These gas supply channels 37 are 30 for the purpose of supplying coke oven gas to the several flame flues of their corresponding heating walls and communicate with the individual flues 19 by means of gas ducts 38 that lead from such channels individually into the bottoms of individual flues. Within the ducts 38 are disposed the usual nozzles 39. The supply of coke oven gas to the channels 37 is derived from coke oven gas 35 mains of the usual type, which may be 40 respectively located on opposite sides of the battery. Suitable means is provided for admitting or cutting off the supply of gas with respect to the channels 37, it being understood that the gas supply is allowed to 45 flow into alternate channels, while the supply is cut off from the intermediate channels.

For operating the battery alternatively 50 with a special generator gas, such as producer gas, the several regenerators H may be optionally connected with a producer gas main, so that the producer gas may be directed into such of the groups of the regenerators H 55 as are operating for inflow and conveyed through these regenerators into burning flame flues 19.

The operation of the inclined retort battery, when employing an ordinary lean gas, 60 such as producer gas, for the fuel is as fol-

lows: The supply of coke oven gas to the coke oven gas main and to all of the coke oven gas channels 37 is cut off. A supply of producer gas is permitted to flow into the alternate regenerators H, such as are operating for inflow and passing through such groups of regenerators is preheated before being delivered into the burning flame flues. During the inflow of producer gas through such alternate groups of regenerators H, waste gas from the down burning flues is flowing out through the outflow regenerators G as well as through the regenerators H, constituting the groups that are intermediate such alternate regenerators. In the regenerators G of the before mentioned alternate inflow groups, inflow of air is maintained and passing upwardly through such regenerators, the air finally enters the burning flame flues to support the combustion of the producer gas that is delivered thereto by the alternate regenerators H. On reversal of the flow, the inflow regenerators become outflow regenerators and concurrently the outflow regenerators become inflow regenerators.

In operating the battery with coke oven gas, the supply of producer gas to inflow regenerators H is shut off and air is permitted to flow into such regenerators in place of the producer gas. During coke oven gas operation, a supply of coke oven gas is maintained in the channels 37 which feed the upburning flues. The reversing mechanism is operated at each reversal to 100 place all of the inflow operating regenerators in communication with the outer air and concurrently all of the outflow operating regenerators in communication with the exhaust.

The invention as hereinabove set forth is embodied in a particular form of construction but may be variously embodied within the scope of the claims hereinafter made.

I claim:

1. In an inclined retort battery, in combination: a plurality of inclined retort chambers; heating walls contiguous to said retort chambers and respectively constituted of vertical combustion flues, the flues of each heating wall being disposed into individual inside and outside groups; inclined bus flues in each heating wall and respectively companion to and communicably connected with the individual inside and outside groups of said combustion flues; the inclined bus flues being also communicably connected with the corresponding bus flues of an adjacent heating wall; regenerators disposed in tiers at a lower level than said combustion flues and constituted of pairs of crosswise groups, with a pair of such regenerators corresponding to and communicably connected with a group of such combustion flues; and means common to each crosswise group of regenerators.

ators for controlling the direction of flow through all of the regenerators of the group; substantially as specified.

2. In an inclined retort battery, in combination: a plurality of inclined retort chambers; heating walls contiguous to said retort chambers and respectively constituted of vertical combustion flues, the flues of each heating wall being disposed into individual groups; inclined bus flues in each heating wall and respectively companion to and communicably connected with the individual groups of said combustion flues; the inclined bus flues being also communicably connected with the corresponding bus flues of an adjacent heating wall; regenerators disposed in tiers at a lower level than said combustion flues and constituted of pairs of crosswise groups, with a pair of such regenerators corresponding to and communicably connected with a group of such combustion flues; and means common to each crosswise group of regenerators for controlling the direction of flow through all of the regenerators of the group; substantially as specified.

3. In an inclined retort battery, in combination: a plurality of inclined retort chambers; heating walls contiguous to said retort chambers and respectively constituted of vertical combustion flues, the flues of each heating wall being disposed into individual inside and outside groups; inclined bus flues in each heating wall and respectively companion to and communicably connected with the individual inside and outside groups of said combustion flues; the inclined bus flues being also communicably connected with the corresponding bus flues of an adjacent heating wall; and regenerators disposed in tiers at a lower level than said combustion flues and constituted of pairs of crosswise groups, with a pair of such regenerators corresponding to and communicably connected with a group of such combustion flues; substantially as specified.

4. In an inclined retort battery, in combination: a plurality of inclined retort chambers; heating walls contiguous to said retort chambers and respectively constituted of vertical combustion flues, the flues of each heating wall being disposed into individual groups; inclined bus flues in each heating wall and respectively companion to and communicably connected with the individual groups of said combustion flues; the inclined bus flues being also communicably connected with the corresponding bus flues of an adjacent heating wall; and regenerators disposed in tiers at a lower level than said combustion flues and constituted of pairs of crosswise groups, with a pair of such regenerators corresponding to and communicably connected with a group of such combustion flues; substantially as specified.

5. In an inclined retort battery, in combination: a plurality of inclined retort chambers; heating walls contiguous to said retort chambers and respectively constituted of vertical combustion flues, the flues of each heating wall being disposed into individual inside and outside groups; inclined bus flues in each heating wall and respectively companion to and communicably connected with the individual inside and outside groups of said combustion flues; the inclined bus flues being also communicably connected with the corresponding bus flues of an adjacent heating wall; and regenerators communicably connected with said combustion flues; substantially as specified.

6. In an inclined retort battery, in combination: a plurality of inclined retort chambers; heating walls contiguous to said retort chambers and respectively constituted of vertical combustion flues, the flues of each heating wall being disposed into individual groups; inclined bus flues in each heating wall and respectively companion to and communicably connected with the individual groups of said combustion flues; the inclined bus flues being also communicably connected with the corresponding bus flues of an adjacent heating wall; and regenerators communicably connected with said combustion flues; substantially as specified.

7. In an inclined retort battery, in combination: a plurality of inclined retort chambers; heating walls contiguous to said retort chambers and respectively constituted of vertical combustion flues, the flues of each heating wall being communicably connected with the flues of another heating wall; and regenerators communicably connected with said combustion flues; substantially as specified.

8. An inclined regenerative heating structure comprising: a retort chamber, flued heating walls respectively constituting the opposite side walls of said retort chamber, the flues of the heating walls being communicably connected with each other by duct means extending over the top of the retort chamber, reversible means for maintaining combustion in alternation in said heating walls, so that gases produced by the combustion in one heating wall may be drawn off through the other, and reversible regenerators respectively connected with said heating walls; substantially as specified.

9. An inclined regenerative heating structure comprising: a retort chamber, flued heating walls respectively constituting the opposite side walls of said retort chamber, the flues of the heating walls being communicably connected with each other by duct means extending across the retort chamber, reversible means for maintaining combustion in alternation in said heating

walls, so that gases produced by the combustion in one heating wall may be drawn off through the other, and reversible regenerators respectively connected with said 5 heating walls; substantially as specified.

10. In an inclined retort battery having a plurality of inclined retort chambers, and heating walls contiguous to said retort chambers, the improvement characterized by 10 regenerators disposed in crosswise groups individual to the respective heating walls, and means common to all the regenerators of each group for controlling the direction of flow through said regenerators; substantially 15 as specified.

11. In an inclined retort battery having a plurality of inclined retort chambers, the improvement characterized by heating walls constituted of vertical flues disposed 20 into inside and outside groups all of the flues of a given wall being adapted to pass the gases in the same direction, and means for effecting individual regulation of the flow through said groups; substantially as 25 specified.

12. In an inclined retort battery having a plurality of inclined retort chambers, the improvement characterized by heating walls constituted of individually regulable 30 groups of flame flues, combined with regenerators individual to said groups; substantially as specified.

13. In a retort battery, in combination: a plurality of retort chambers, heating walls 35 contiguous to said retort chambers and respectively constituted of combustion flues,

the flues of each heating wall being disposed into individual inside and outside groups; bus flues in each heating wall respectively companion to and communicably connected with the individual inside and outside groups of said combustion flues; the bus flues being also communicably connected with the corresponding bus flues of an adjacent heating wall; substantially as specified. 40 45

14. In a retort battery having a plurality of retort chambers, the improvement characterized by heating walls constituted of flues disposed into inside and outside groups, all of the flues of a given wall being adapted to pass only burning or only waste gases, and means for effecting individual regulation of the flow through said groups; substantially as specified. 50 55

15. A retort battery having a plurality of retort chambers and heating walls constituted of flues disposed into inside and outside groups, all of the flues of a given wall being adapted to pass only burning or only waste gases. 60 65

16. In a retort battery having a plurality of retort chambers, the improvement characterized by heating walls each constituted of individually regulable groups of flues, all of the flues of a given wall being adapted to pass only burning or only waste gases, combined with regenerators individual to said groups, substantially as specified. 70

In testimony whereof I have hereunto set my hand.

JOSEPH BECKER.
